UNITED STATES PATENT OFFICE.

ALONZO LINTON BAUSMAN, OF CHICOOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

FILTER-PRESS.

1,331,453.

Specification of Letters Patent. Patented Feb. 17, 1920.

Application filed October 2, 1918. Serial No. 256,526.

To all whom it may concern:

Be it known that I, ALONZO LINTON BAUSMAN, a citizen of the United States of America, residing at Chicopee, in the 5 county of Hampden and State of Massachusetts, have invented certain new and useful Improvements in Filter-Presses, of which the following is a specification.

This invention relates to an improvement 10 in hydraulic filter presses. Such presses are used to extract cocoa butter from cocoa liquor and this particular use will be described in connection with the invention. Broadly, however, the invention is applicable where a large percentage of liquid 15 needs to be separated or filtered from the solid contents of a mixture under pressure.

According to my invention the structure and mode of operation have been improved 20 to the end that the desired work may be done more economically and efficiently than with structures heretofore used for the purpose. It is to this object that my invention is directed. The manner of accomplishing 25 such object will be apparent from a description of one preferred form now to be disclosed for purposes of illustration. The scope of the invention will be covered in the annexed claims read in the light of the 30 required disclosure. The specific disclosure is not intended to limit the scope of the claims.

Referring now to the drawings:

Figure 1 is a longitudinal section of a 35 press with parts broken away;

Fig. 2 is a section on line 2—2 of Fig. 1 with many parts omitted from such figure added in this one;

Fig. 3 is a detail of the cocoa collecting 40 ring;

Fig. 4 is a detail sectional view with parts in one position.

Fig. 5 is a detail sectional view with some 45 parts of Fig. 4 removed and others in a different position to bring out the mode of operation.

Common practice in these presses includes a hydraulic press with head 8, cylinder chamber 14, piston 11, pressure abutment 12, 50 and spaced abutment 7 all suitably mounted in a strong frame so that abutment 12 may move toward abutment 7 under the hydraulic head and be returned by means connected at 15.

Under the pressure between abutments, a 55 series of unit structural filter groups are designed to operate for the filtering purpose. One only of such series will be described. The others are preferably of the same kind so that the parts may be standardized. 60

The purpose of the press is to first filter under the hydraulic pressure of the material itself. When this filtering action results in a collection of semi-solid material in the press to interfere with the filtering action, 65 then the second purpose is to put such material under the pressure of an independent hydraulic head between abutments of the press whereby the liquid in such material is forced through the filter and the separation 70 of liquid from solid is completed.

To accomplish this purpose by improved means and mode of operation, I provide for a filtering group, which includes a metal filtering plate 22, a metal plunger plate 42, 75 and a metal collecting ring 54. This group and its operation with the press will now be described.

The plate 22 rests by shoulders 33 on longitudinal beams 10 of the press. Plunger 80 plate 42 is joined in abutment against one face of plate 22 by nipple 40' to leave a central opening O through both plates. Over the outside faces of plates 22 and 42, filtering disks 36 and 50 preferably of felt 85 are respectively fastened by screws and the clamping annulus 51. On both faces of each plate are a series of concentric grooves 37, 38, 43, and 45.

A series of passages 39, formed in plate 90 22 and disposed parallel to the axis thereof, serve to connect each groove 37 on one face of the plate to the corresponding groove 38 on the opposite face of the plate. The grooves 43 and 45 on opposite faces of plate 95 42 are similarly connected by passages 44. A series of radial grooves 46 are provided, on that face of plate 42 adjacent plate 22, to connect the several grooves 43 one to the other, and, on that face of plate 22 adjacent to plate 42, there are provided in the lower portion a series of radial grooves 40 which extend to the outer periphery of plate 22. 100

The plunger ring 52 extends peripherally 105 around plate 42 and a tight but movable joint is made therebetween by means of the cup washer or packing 47 (preferably of

leather) fastened in a recess adjacent the circumference by metal ring 48 as indicated in Fig. 5.

The collecting ring 54 (shown in Fig. 3) 5 is adapted by suitable shoulders to rest on beams 10 in line with the plunger ring. The latter has a packing 53 to make a tight joint under pressure all around ring 54.

The spacing fingers 21 are pivoted at 34 to 10 plate 22 (see Fig. 2) and may be moved from the spacing position (in Fig. 4) to dotted line position (indicated in Fig. 2) out of alignment with ring 52 and plate 22. The chain connected shafts 28 and gear connections 27 are turned by hand wheel 32, whereby the cam shafts 26 and cams 25 bear on or release the outer ends of 23 and 24 of all of the spacing fingers of the series of sets to position them as desired. The gears 15 are carried by suitable brackets 7 in the press frame and the latter is firmly braced by the longitudinal spacing bars 9 and beams 10 connecting the frame heads (not shown).

The operation of the improved press will 25 now be readily understood. The series of unit groups are first mounted between abutments 12 and 7 as indicated in Fig. 1 and in a group detail in Fig. 4. It will be noticed that spacing fingers 21 cause plunger rings 30 52 to occupy an offset relation to plunger plates 42 equal to the width of the fingers. The abutment 12 is moved to hold the groups in tight relation whereby, on account of the packing 53, 47, and the felts 36, there will be 35 no outlet for the liquor in the press except through the filtering felts 36 and 50. The liquor is now forced through pipe 17 and openings O to fill all the available space in the press. This will be the spaces in between a plate 22 of one group and plunger head 42 of the next group. A sufficient 40 pressure or hydraulic head back of the liquor will force the cocoa butter to filter through the felts 36 and 50 and leave the press by 45 means of the plate grooves to fall in pan 19 on warming device 20. This pressure is continued until the cocoa butter practically 50 stops coming from the press. This event evidences the fact that a mass of semi-liquid 55 having a large percentage of cocoa solids occupies space m and interferes with the further filtering of the liquid. The first step including the introduction of additional liquid has now gone as far as possible.

55 The second operating step of my structure which gives the above results will now be described. The valve 18 is turned to prevent any flow whatever through pipe 17. The pressure of plate 12 is released enough 60 to permit the turning of hand wheel 32 to move spacing fingers 21 from between plates 22 and plunger rings 52. Hydraulic pressure of sufficient amount is then put back of piston 11 to move the unit groups together 65 the distance they have formerly been kept

apart by the spacing fingers. This distance is enough to cause the plunger plates 42 to enter and take up the offset with plunger rings 52. The change in the position of the parts is indicated by the difference of relative positions of the parts in Figs. 1 and 4 with respect to the parts in Fig. 5.

70 It is quite obvious that enormous pressure is necessary for the result and under this pressure and the resultant movement it 75 should be particularly noted that the felts 36 are effectively clamped against their plates by collecting rings 54 so there can be no destructive movement by these felts. The felts 50 move in snug but not packing engagement with relation to the smooth interior of plunger rings 52 and never leave these rings which, with the independent packings 47 and 53, act as protectors for the felts 50. The felts are never forced from 80 one ring to another but are effectively protected in the severe service of getting the last drop of butter out of the cocoa cake. The latter, or collected solids, is 85 in collecting rings 54. Since, as shown in 90 Fig. 5, the plunger plate 42 is not advanced into the circle of the collecting plate 54, the collecting plate with its contents can be 95 lifted out of the assembly without the necessity of separating the two plates longitudinally.

The critical parts of the press are provided by my invention for an improved mode of operation and the greater convenience in arranging them for such operation 100 as well as separating them afterward.

What I claim is—

1. In a press of the character described, a filtering plate, a plunger plate in face abutment therewith, a filtering cloth on the outside face of each plate, a collecting ring designed to press the cloth against the filter plate and a plunger ring independent of said collecting ring and designed to surround and protect the edges of the cloth on 105 the plunger plate at all times when in service, and a packing between the plunger ring and plunger plate and independent of the filtering cloth carried upon said plunger ring.

110 2. In a press of the character described, a plunger plate, a filtering cloth covering the pressing face thereof, a collecting ring, a plunger ring for spacing said plate and collecting ring each from the other, said plate 115 and rings being relatively movable and so proportioned that upon maximum approaching movement the pressing face of said plunger plate is brought to the plane of said collecting ring but, by virtue of said plunger ring, is not insertible therein.

3. In a press of the character described, a plunger plate, a filtering cloth covering one face of the plate, a plunger ring to protect the cloth and within which the plate is de- 130

signed to move, a collecting ring, and packing between the two rings and between the plunger and its ring, whereby when the plate and rings are forced together under great pressure leaks are prevented independently of the filtering cloth.

4. In a press of the character described a filtering plate and a plunger plate, each with a filtering face and arranged back-to-back, a collecting ring spaced from the plunger plate, a plunger ring operatively between said collecting ring and said plunger plate, and a spacing means optionally insertible operatively between said plunger ring and said plunger plate, the relative dimensions of the said elements being such that, upon removal of said spacing means and approach of said plunger plate and collecting ring, such plate is brought to the plane of said collecting ring but, by virtue of said plunger ring, is not insertible therein.

5. In a filter press adapted for hydraulic-head and plunger-pressure filtration, in combination, a plunger plate provided with an abutment, a plunger ring dimensioned to receive said plate, an optionally active spacing means between said abutment and said plunger ring to prevent, when active, advance of said plunger in said ring, a collecting ring arranged at the other side of

said plunger ring from said spacing means, and means for relatively moving said plate and rings to advance said plate in said plunger ring and move said plunger plate 35 and said collecting ring toward each other, when said spacing means is inactive.

6. In a filter press adapted for hydraulic-head and plunger-pressure filtration, in combination, a plunger plate provided with 40 an abutment, a plunger ring dimensioned to receive said plate, an optionally active spacing means between said abutment and said plunger ring to prevent, when active, advance of said plunger in said ring, a collecting ring arranged at the other side of said plunger ring from said spacing means, and means for relatively moving said plate and rings to advance said plate in said plunger ring and move said plunger plate and said 45 collecting ring toward each other, when said spacing means is inactive, said plunger plate and plunger ring being relatively dimensioned, and said abutment being located, to provide that upon maximum approach of said plunger plate and said collecting ring, said plunger plate is brought to the plane of said collecting ring but, by virtue of said plunger ring, is not insertible therein. 50 55

ALONZO LINTON BAUSMAN.
